UNITED STATES PATENT OFFICE.

DENIS FLANAGAN, OF CLAYTON-LE-MOORS, ENGLAND.

BLINDSTITCH SEWING-MACHINE.

No. 856,999.

Specification of Letters Patent.

Patented June 11, 1907.

Original application filed June 11, 1904, Serial No. 212,136. Divided and this application filed July 3, 1905. Serial No. 263,197.

To all whom it may concern:

Be it known that I, DENIS FLANAGAN, a subject of the King of Great Britain and Ireland, and a resident of Clayton-le-Moors, in the county of Lancaster, England, works manager, (whose post-office address is 26 Oswald street, Clayton-le-Moors,) have invented certain new and useful Improvements in Blindstitch Sewing-Machines, of which the following is a specification, being divided out of the pending application No. 212,136, filed June 11, 1904.

This invention relates to improvements in blind stitch sewing machines or to such machines in which the needle instead of passing at right angles through the cloth passes, on the other hand, in a direction more or less parallel with the plane of the cloth and only through a portion of the thickness so that the stitches do not show on the face of the cloth.

The invention relates to improvements in the means for holding the fabric to be stitched, for adjusting part of the holding means with relation to the needle and to other details which will be fully pointed out, in the following description and claims.

The invention will be fully described with reference to the accompanying drawings in which

Figure 1 is a side elevation of the machine with my improvements attached, partly in section, Fig. 2 plan partly in section, Fig. 3 end elevation of same partly in section, Fig. 4 transverse section of cloth plate to enlarged scale showing means of operating a slideable plate carried by the former, Fig. 5 plan of same, Figs. 6 and 7 end elevation and plan, respectively, to enlarged scale of modified arrangement of slideable plate and Fig. 8 part longitudinal section of cloth plate, to enlarged scale, showing modified means of locking the plate in working position.

My invention particularly relates to that class of blind-stitch sewing machine in which a substantially flat arm overhangs its point of support so that its free end lies in proximity to the needle and is adapted to have folded round it the material to be stitched.

In the drawings like parts are indicated by the same reference letters, and it should be said that the whole of the mechanism above the table is of the ordinary character used in these machines and as it forms no part of my invention is not illustrated beyond indicat-

ing the main carrying arm *a*, the fly wheel *b*, with its grooved pulley.

My invention comprises an arm *d*, arranged longitudinally of the machine. It is formed in one with or connected to a vertical pivot *d'* passing through a stationary pivot bearing *d'''* fixed in the bed *d''* of the sewing machine. This pivot is to enable the plate to be lifted vertically and to be turned about it away from the machine in the direction of the arrow in Fig. 2 to the position indicated by broken lines in the same figure or out of its normal working position to enable the shuttle to be readily placed into or taken from its carrier *e* without turning the whole body of the machine over. It should here be said that the shuttle and its operating mechanism form no part of my invention and may be of any ordinary type. A further object in the arrangement of the cloth plate is to enable it to be raised while the material to be stitched is being placed in position and afterward to be easily dropped down on the material prior to commencing sewing. By means of a spring *e'* the cloth plate is pressed in a downward direction, the spring being adjusted by means of a nut *e''*. When in the lowermost position the cloth plate is held absolutely rigid both with relation to the needle and with respect to any thickness of cloth or other material which may be passed round it to be operated upon. *f*, Fig. 3 indicates the position of the cloth.

The plate may be readily lifted to enable the fabric to be put under by simple means, preferably, by a rotatable collar *g*, surrounding the vertical stationary pivot bearing *d'*, such collar having one or more studs *g'* engaging with one or more screw grooves *g''* in the bearings *d'* so that as the collar is rotated it will also rise against the underside of the plate and lift it up against the pressure of the spring *e'*. The collar may be rotated by a knob or handle *g'''* and the extent of its rotary movement determines the vertical rise so that the cloth may be passed between the feed wheels, without altering the position of the cloth plate, longitudinally. A greater rotary movement of the collar lifts the cloth plate still further vertically so that it may be turned about its pivot to a position more or less at right angles to the bed of the machine, as indicated in Fig. 2, in which position it is entirely out of the way of the needle and shuttle mechanism, enabling the lat-

ter to be easily available for changing shuttles. To lock the cloth plate in position rigidly, during the normal working of the machine, a projecting portion h near to the pivot 5 d' is adapted to engage with a vertical groove h' in the bed of the machine in which it fits tightly. Or in place of this groove I may employ in the bed d'' a pin or stud h''' , preferably tapered and have a corresponding hole h'''' in the underside of the cloth plate d so that as the latter is pulled downward by the spring e' the parts will be locked together and the inward longitudinal side of the cloth plate will be held perfectly rigid 15 and within a defined distance from the flat face of the needle employed in this class of machinery. This latter arrangement is shown in Fig. 8.

Instead of moving the whole of the cloth plate bodily to adjust it to and from the flat face of the needle to determine the depth such needle shall penetrate into the cloth I employ a separate adjustable plate i arranged transversely of the cloth plate d on 20 its upper surface. This plate has a rounded edge i' at the side nearest to the needle. The plate is adjusted by arranging it in transverse grooves i'' in the cloth plate and by the employment of an eccentric stud i''' 25 passing through the plate, a cylindrical portion of the stud passing through a hole i'''' in the cloth plate d . The eccentric stud can be turned about its center by a lever j , preferably below the cloth plate, the movement of 30 this lever causing the adjustable plate to be readily moved nearer to or farther from the needle. A stop j' is used to prevent the adjustable plate being moved against the needle, and, further, the lever may be locked in 35 any suitable position required by simple means, if necessary. The lever is held in position on the stud by nuts j'' .

The rounded edge of the adjustable plate i may be hardened to prevent wear, or, instead of rounding it, I may employ a small roller k mounted in its front edge as indicated 45 in Figs. 6 and 7.

From the foregoing description it will be seen that the whole of the parts are simple in 50 construction, positive in operation and efficiently arranged for their purpose.

What I claim as my invention and desire to protect by Letters Patent is:—

1. In a blind stitch sewing machine the

means for holding and supporting the fabric 55 to be operated upon consisting of a cloth plate with an overhanging end arranged longitudinally of the bed of the machine, a vertical pivot for supporting said plate along the axis line of which it can be raised in horizontal planes parallel with the top plane surface of the bed and about which axis it can be rotated away from the sewing needle substantially as and for the purposes described.

2. In a blind stitch sewing machine the 65 means for raising and lowering the cloth plate consisting of a vertically arranged pivot formed integral with the cloth plate, a stationary pivot bearing fixed in the bed of the machine, screw grooves formed in the interior 70 of said bearing, a loose collar mounted upon the bearing, projections in the interior of the collar engaging with the screw grooves, and means for rotating said collar substantially as described.

3. In a blind stitch sewing machine the means for raising and lowering the cloth plate consisting of a vertically arranged pivot on the underside of the cloth plate, a stationary pivot bearing fixed in the bed of the machine, 80 screw grooves formed in the exterior of said bearing, a loose collar mounted upon the bearing between the underside of the cloth plate and the bed of the machine, projections in the interior of the collar engaging with the 85 screw grooves a handle on the exterior of the collar for rotating such a spring surrounding the lower end of the pivot and means for adjusting said spring substantially as described.

4. In a blind stitch sewing machine the 90 combination with the fabric supporting plate of an adjustable plate located in grooves on the upper side of said supporting plate, and means for moving the adjustable plate toward and from the sewing needle, consisting 95 of an eccentric stud passed through the plate and the supporting plate, a slot in the supporting plate, a bush in the slot surrounding the eccentric stud, a lever mounted on the stud and means for securing the lever in position substantially as described.

In testimony whereof I have hereunto set my hand in the presence of two witnesses.

DENIS FLANAGAN.

Witnesses:
